TELEVISION ANTENNA

Ralph N. Leonard, Crystal Lake, and Elmer G. Hills,
Des Plaines, Ill., assignors to Radion Corporation, Chi-
cago, Ill., a corporation of Illinois

Application March 3, 1955, Serial No. 34,847

Term of patent 14 years

(Cl. D26—14)

Fig. 1

Fig. 2

Fig. 3

Fig. 1 is a perspective view of a television antenna, embodying the new design of the present invention;

Fig. 2 is a top plan view of the television antenna of Fig. 1; and

Fig. 3 is a back elevational view of the television antenna of Fig. 1.

The broken lines are shown for illustrative purposes only.

We claim:

The ornamental design for a television antenna, substantially as shown and described.
